(21) Appl. No.: **29/844,637**

Primary Examiner — Wan Laymon

(22) Filed: **Jun. 30, 2022**

(74) Attorney, Agent, or Firm — Tarter Krinsky & Drogin LLP

(51) LOC (14) Cl. .... **07-99**(57) **CLAIM**

(52) U.S. Cl.

The ornamental design for an ice head wrap, as shown and described.

(53) USPC .... **D24/207**(58) **Field of Classification Search**

DESCRIPTION

USPC D24/206–208, 200, 191; D2/865, 870,
D2/878; D29/106
CPC A61F 7/00; A61F 7/02; A61F 7/10; A61F
7/106; A61F 2007/0002; A61F
2007/0063; A61F 13/12; A41D 20/005

See application file for complete search history.

(56) **References Cited**

FIG. 1 is a side perspective view of the ice head wrap showing the present design.

FIG. 2 is a front view thereof.

FIG. 3 is a rear view thereof.

FIG. 4 is right side view thereof.

FIG. 5 is a left side view thereof.

FIG. 6 is a top view thereof.

FIG. 7 is a bottom view thereof; and,

FIG. 8 is perspective view of the ice head wrap shown in use. The portions of the design shown in broken lines being for the purpose of illustrating environment only and form no part of the claimed design.
